UNITED STATES PATENT OFFICE.

ARTHUR R. THOMPSON, OF CHICAGO, ILLINOIS, ASSIGNOR OF ONE-HALF TO CHARLES C. FOX, OF CHICAGO, ILLINOIS.

SAFETY DEVICE FOR MONEY-DRAWERS, &c.

1,370,167.

Specification of Letters Patent.

Patented Mar. 1, 1921.

Application filed January 26, 1920. Serial No. 354,077.

To all whom it may concern:

Be it known that I, ARTHUR R. THOMPSON, a citizen of the United States, residing at Chicago, in the county of Cook and State 5 of Illinois, have invented new and useful Improvements in Safety Devices for Money-Drawers &c., of which the following is a full, clear, and exact description.

Heretofore the methods employed, in 10 banks and other business establishments in stacking piles of money and valuables in exposed positions in drawers, or the tops of desks, in show cases and in show windows, is a constant inducement to thieves 15 and burglars to rob and steal, because of the comparative ease with which they can reach and get possession of the property and successfully commit their depredations.

The object of my invention is to enable 20 the officials or employees of a bank or store, or any of them, to promptly, the instant there is any kind of danger, dump the contents of the desk or drawer, or show case or show window, or other support on or in 25 which such valuables, etc. are placed, into a chute, down which they will gravitate into a place of safety where they cannot be reached within the period of time usually at the disposal of the marauders, and to enable this to be done without the display of 30 such personal actions as would apprise the thieves or robbers as to how and by whom it was done.

This I accomplish through the medium of 35 the mechanism hereinafter described, and as illustrated in the drawings, in which like reference numerals represent corresponding parts.

In the drawings—
40 Figure 1 is a vertical section of a desk showing a side view of my improvements which are applied thereto.
Fig. 2 is a vertical section of my improved drawer and desk drawn to a larger scale.
45 Fig. 3 is a plan view of the desk showing a portion of the top broken away to disclose portions of my invention.

Fig. 4 is a vertical section taken on dotted line 4, 4, Fig. 2.

Fig. 5 is a horizontal section taken on 50 dotted line 5, 5, Fig. 2.

Fig. 6 is a vertical section taken on dotted line 6, 6, Fig. 5.

Fig. 7 is a diagrammatical view of the electrical layout of two drawers embodying 55 my improvements.

Fig. 8 is a sectional view of a fragment of my invention.

Fig. 9 is a front elevation of my invention showing the lefthand inclined chutes, 60 and the superposed mechanism connected therewith, broken away.

In the drawings A represents the top of a high desk; B the vertical side walls of the same, between which the sliding drawer 65 embodying my invention is supported, and C a suitable chute that may be made of any suitable shape so long as it is large enough to receive the discharge from said drawer and lead downward from a point, just below 70 said drawer, either in a perpendicular or inclined direction to one side or the other, to a suitable receptacle below the floor D.

The drawer above referred to is rectangular in horizontal section, and the upper edges 75 of its front wall 10, its side walls 12, and its rear wall 13, are all in the same horizontal plane. The height of the front wall is much less than that of its rear wall, and the front edges of the side walls, below the 80 lower edge of the front wall, are inclined to the rear, thus, when looking at the sides of the side walls they have the appearance of a trapezoid whose upper front angle is truncated.

The rectangular bottom 14 of this drawer has its front edge hinged, by means of suitable hinges 15, 15, to the lower edge of the front wall, and its rear transverse edge terminates a suitable distance in front of 90 the rear wall 13. Just above this rear edge the drawer is provided with a transverse partition 16 that forms the back of the portion of the drawer that is designed to re-

ceive the valuables or other matter it is desired to have conveniently at hand. If desired this portion may be divided into several divisions, as, for instance, by a longitudinal partition 17, connecting said transverse partition 16 with the front wall 10.

The rear edge of the bottom 14 is supported by a transversely disposed bar 18, the ends of which extend into suitable longitudinally elongated slots 19, 19, in side walls 12, 12. This bar is movable bodily to and from the rear edge of bottom 14 of the drawer and when it moves rearward said bottom drops or dumps, and when it moves forward it is adapted to move under said rear edge, when the bottom is in a horizontal position, and support the same. Bar 18 is kept pressing toward the front of the drawer by means of longitudinally disposed coil-springs 20, 20, that are interposed between the extended ends of said bar and blocks 21, 21, secured to the outer surfaces of the side walls of the drawer, in channels, formed between the rear portions of the longitudinal supporting cleats, 22, 22, secured to the outer surfaces of the side walls of the drawer and superposed strips 23, 23, which latter are suitably secured to said side walls and are separated from and parallel to the rear portions of the cleats.

When bottom 14 drops down, the contents of the drawer are dumped into the chute C and gravitate therein into the receptacle provided to receive them, as hereinbefore stated. This may be accomplished by moving the bar 14 rearwardly in one of several ways, manually or electrically.

In order to accomplish this electrically, I provide the rear edge of bar 18 with a strip 40 of soft metal 24, that is suitably secured thereto, and helices that are secured to each end of an overhead cross-bar 25, connecting the sides of the drawer; which helices when energized, attract said strip 24 and move 45 the bar 14 out from under bottom 18 and permit it to dump. These helices are connected, preferably, in series, in the same electric circuit, and wires 27, 27, that lead from the same extend to and connect with a metal 50 contact strip 28, secured to the under edge of the supporting-cleats. These supporting-cleats 22, 22, are secured to the sides of the desk, and the upper or engaged surfaces of these guide-cleats are also provided with 55 metal contact-strips 30, 30, that are always engaged by contact-strips 28, no matter in what position the drawer may be in. The wires 31, and 32 of the circuit leading from strips, 30, 30, are respectively, connected up 60 with the necessary primary battery 32 or other source of electrical energy, and one of them has a switch or push-button 33 connected therewith which may be located on the floor or any other place where it can be 65 conveniently reached and instantly operated

to close the circuit and release the bottom of the drawer, as hereinbefore explained.

In order to operate and dump bottom 14 manually a U-shaped wire yoke or bail 35 is employed. The ends of this bail are secured to the ends of the releasing bar 18 and from thence the parallel legs of the same extend longitudinally forward above cleats 22, until under the front wall of the drawer, where they are connected by the transverse stretch of the bail. This transverse stretch may be made of wood, if desired, and when it is desired to dump the drawer the operator quickly pushes against this transverse stretch of frame 35 and bottom 14 instantly 80 drops.

In order to restore bottom 14 to its horizontal position after it has been dumped, a rectangular panel 36 is pivotally connected at about the center of length of its side edges 85 to the side walls of the drawer, just back of the inclined forward edges of the same. The center of width of this panel near its upper edge is provided with a finger slot 37, and when the bottom 14 is in its downwardly 90 fallen position, it can be restored to its horizontal position again by swinging the upper edge of said panel downward upon its pivots and causing the lower edge thereof to engage and lift the bottom up until the rear 95 edge of the latter engages the front edge of bar 18. The front edge of this bar is, preferably, given an undercut bevel, and the rear edge of the bottom engages this under cut beveled edge, as it is swung upward and forces the bar 18 rearward and passes above it, whereupon the bar is forced forward under said bottom by springs 20, 20. When the panel is released its weight is so disposed 100 on its pivots that it automatically gravitates into the position where it closes the front of the drawer below the front wall thereof.

I do not desire to be confined to the exact construction of my invention as hereinbefore described, as it is obvious the details thereof might be changed and modified without departing from the general mechanical principle embodied in the same.

Moreover I do not desire to confine the application of my improvements to a drawer, 115 because they could with equal facility be applied to the top of a desk, or the bottom of a show case or the floor of a display window. In either of these events the top of the desk or the bottom of the show case, or the floor 120 of the display window would be substituted for the bottom 14 of the drawer, and remaining mechanism would be the same as that hereinbefore described. All such changes, I desire to be considered as contemplated 125 within the scope of my invention.

What I claim as new is:

1. A contrivance of the kind specified comprising a horizontally slidable receptacle, a bottom therefor which is hinged at one end, 130

movable means carried by and movable with said receptacle that sustains the end of said member opposite its hinge, electrical devices that move said means to withdraw from said 5 end and permit said member to drop, and a chute into which said member discharges.

2. A contrivance of the kind specified comprising a horizontally slidable receptacle, a bottom therefor which is hinged at one end, 10 movable means carried by said receptacle that sustains the end of said member opposite its hinge, devices that move said means to withdraw from said end and permit said member to drop, a chute into which said 15 member discharges, and mechanism for restoring said member to its horizontal position.

3. A contrivance of the kind specified comprising a horizontally slidable receptacle, a bottom therefor which is hinged at one end, movable means carried by said receptacle that sustains the end of said bottom opposite its hinge, devices that move said means to withdraw from said end and 25 permit said bottom to drop regardless of the position of the drawer, a chute into which said bottom discharges, and mechanism that engages both said bottom and means to restore said bottom to and retain the same in 30 its horizontal position.

4. A contrivance of the kind specified comprising a slidable drawer, a bottom therefor that is hinged at one end, means carried by said drawer that is adapted to 35 engage the end of said bottom opposite its hinges, which regardless of the position of said drawer sustains said end and in another releases and permits said bottom to drop, and a chute into which said bottom 40 discharges.

5. A contrivance of the kind specified comprising a slidable drawer, a bottom therefor that is hinged at one end, means carried by said drawer engaging the end 45 of said bottom opposite its hinges, which in one position sustains said end and in another releases and permits said bottom to drop regardless of the position of the drawer, a device carried by said drawer for 50 moving said means, and a chute into which said bottom discharges.

6. A contrivance of the kind specified comprising a slidable drawer, a bottom therefor that is hinged at the front end, a 55 transverse bar engaging the rear end of said bottom opposite its hinges, which in one position sustains said end and in another releases and permits said bottom to drop regardless of the longitudinal position 60 of said drawer, and a chute into which said bottom discharges.

7. A contrivance of the kind specified comprising a slidable drawer, a bottom therefor which is hinged at one end, a trans- 65 verse bar that engages the end of said bot-

tom opposite its hinges and the ends of which are supported and extend through slots in the side walls of said drawer, means for moving said bar to and from the un-hinged edge of said bottom, and springs 70 for pressing said bar toward said edge.

8. A contrivance of the kind specified comprising a slidable drawer, a bottom therefor which is hinged at one end, a trans- 75 verse bar that engages the end of said bot- tom opposite its hinges and the ends of which are supported and extend through slots in the side walls of said drawer, means for moving said bar to and from the un-hinged edge of said bottom, springs for 80 pressing said bar toward said edge, and electrical devices for moving the bar away from said bottom.

9. A contrivance of the kind specified comprising a slidable drawer, a bottom 85 therefor which is hinged at one end, a trans- verse bar that engages the end of said bot- tom opposite its hinges and the ends of which are supported and extend through slots in the side walls of said drawer, means 90 for moving said bar to and from the un-hinged edge of said bottom, springs for pressing said bar toward said edge, electri- cal devices for moving the bar away from said bottom, and a panel pivoted between 95 the sides of said drawer for restoring the bottom to its horizontal position.

10. A contrivance of the kind specified comprising a slidable drawer, a bottom therefor which is hinged at one end, a trans- 100 verse bar that engages the end of said bot- tom opposite its hinges and the ends of which are supported and extend through slots in the side walls of said drawer, means for moving said bar to and from the un- hinged edge of said bottom, springs for 105 pressing said bar toward said edge, electri- cal devices for moving the bar away from said bottom, and a bail the ends of which are secured to the ends of said bar and 110 which passes to and across in front of said drawer.

11. A contrivance of the kind specified comprising a slidable drawer, a bottom therefor which is hinged at one end, a trans- 115 verse bar that engages the end of said bot- tom opposite its hinges and the ends of which are supported and extend through slots in the side walls of said drawer, means for moving said bar to and from the un- hinged edge of said bottom, springs for 120 pressing said bar toward said edge, and a bail the ends of which are secured to the ends of said bar and which passes to and across in front of said drawer. 125

12. A contrivance of the kind specified comprising a slidable drawer, a bottom therefor which is hinged at one end, a trans- 130 verse bar that engages the end of said bot- tom opposite its hinge, armatures secured to

said bar, helices toward which said armatures are attached, supporting cleats secured to the sides of said drawer, contact-strips secured to the undersides of said cleats, a 5 supporting-frame for said drawer, guide-cleats secured to said frame, contact-strips on the upper sides thereof that are engaged by the first mentioned contact-strips, an electric circuit in which said helices and

contact strips are connected and an electrical fixture for opening and closing said circuit. 10

In witness whereof, I have hereunto set my hand this 10th day of January, 1920.

ARTHUR R. THOMPSON.

Witnesses:

FRANK D. THOMASON,
EVA STREIT.
